C. F. LOAR

BURGLAR ALARM

Filed March 24, 1925

FIG. 1.

FIG. 2.

FIG. 3.

UNITED STATES PATENT OFFICE.

CARL F. LOAR, OF SUNBURY, OHIO.

BURGLAR ALARM.

Application filed March 24, 1925. Serial No. 17,942.

To all whom it may concern:

Be it known that I, CARL F. LOAR, a citizen of the United States, residing at Sunbury, in the county of Delaware and State of Ohio, have invented certain new and useful Improvements in a Burglar Alarm, of which the following is a specification.

The present invention relates to a burglar alarm, and aims to provide a novel and improved device of this character which may be readily and conveniently attached to a door for efficiently sounding an alarm to indicate that the door has been opened.

15 A further object of the invention is the provision of a spiral spring adapted to be wound for operating or sounding an alarm upon the opening of a door; the device having means for engaging between the edge 20 of the door and the facing strip of a door frame for preventing operation of the spring motor while the door is in a closed position, the device also having a member arranged for engaging said means positioned 25 between the door and door frame for preventing operation of the alarm independent of the position of the door.

It is also an object of the invention to provide a burglar alarm of the kind indicated, which is simple and substantial in construction, which can be manufactured economically, and which will be thoroughly efficient and practical in use.

With the foregoing and other objects in view, which will be apparent as the description proceeds, the invention resides in the construction and arrangement of parts, as hereinafter described and claimed, it being understood that changes can be made 35 within the scope of what is claimed without departing from the spirit of the invention.

The invention is illustrated in the accompanying drawings, wherein:

45 Figure 1 is a fragmentary elevation of a door and door frame, showing my improved device applied,

Figure 2 is a section taken on line 2—2 of Figure 1,

50 Figure 3 is a section taken on line 3—3 of Figure 2,

Figure 4 is a fragmentary horizontal section taken on line 4—4 of Figure 3; and

55 Figure 5 is a fragmentary section showing a manner in which the device may be attached to a door.

Referring to the drawings, the numeral 10 designates a portion of a door frame hingedly connected, as at 11, for pivotally supporting a door 12, which is shown for illustrating the manner in which my improved device may be applied to a door. In carrying out the invention, the numeral 13 indicates a main body plate having a pair of parallel spaced extension members 14 carried at one end thereof, which have their free ends bent at right angles, as at 15, for engaging between the edge of the door 12 and the door frame 10. On the inner face of the angularly bent portions 15 are provided small prongs 16 which are adapted to be forced into the edge of the door. At the opposite end from that which said extensions 14 are provided on the plate 13 is provided another pair of parallel spaced 70 extensions 17 arranged for supporting a rubber suction cup 18, said rubber suction cup 18 having a reduced neck 19 into which the extensions 17 extend and a head 20 for engaging over portions of the outer surfaces of said extensions. Hingedly connected to the free end of one of the extensions 17 is a small plate 21 carrying a prong 22 which is adapted to be forced into the side of the door should the surface of the door be rough or irregular so that the suction cup 18 will not hold the device in a rigid manner to the door.

Supported in a spaced position from the plate 13 is another plate 24 smaller in size 90 than the plate 13 and held in such spaced position by angled supporting members 25, the opposite ends of which are attached to said plates. Pivotally mounted centrally of the plates 13 and 24 is a shaft 26, to which is secured one end of a spiral spring 27 which in turn has its opposite end attached to a stationary shaft 28 supported between said plates 13 and 24. Secured to the rotatable shaft 26 adjacent the spring 100 27 is a gear 29 meshing with a small gear 30 carried by another shaft 31 which is also pivotally supported between the plates 13 and 24. The shaft 31 also has secured thereto another gear 32 which engages a double action pawl 33 for alternately turning the same on its pivot. Secured to the pivot pin of the pawl 33 is a hammer 34 arranged for striking a bell 35 mounted on the shaft 26 and arranged about the plate 110 24. The outer end of the shaft 26 is screw threaded for receiving a cap 36 which has

attached thereto a handle 37 arranged for rotating the shaft 26 in order to wind the spiral spring 27. Positioned on the plate 13 is an angled member 38 having the arm 39 thereof arranged between the spaced angularly bent portions 15 of the extensions 14 for engaging between the edge of the door 12 and door frame 10 with the angled bent portions 15 of said extensions. The other 10 arm 40 of the angled member 38 has a slot 41 provided therein through which extends a pin 42 carried by the plate 13 in order to support the angled member 38 in a manner that the same may slide upon the plate 13. One of the extensions 14 has its inner edge turned up to provide a guide for directing the sliding movement of the angled member 38, said guide engaging the edge of the angled member. Carried by the free 20 end of the arm 40 of the angled member 38 is a V-shaped lug 44 for engaging between the teeth of the gear 32 in order to prevent rotation of said gear, when the angled member 38 is slid or positioned in an 25 inward manner.

One side of the arm 40 of the angled member 38 is notched, as at 45, so as to provide a shoulder 46 to be engaged by the end 47 of a lever 48 pivotally connected to the plate 13, as at 49. The lever 48 is arranged to be swung in a position to engage in the notch 45 so as to hold the angled member in a position with the V-shaped lug carried thereby received between the teeth of the 30 gear 32. Secured to the plate 13 on the opposite side of the arm 40 of the angled member 38 from that carrying the lever 48 is one end of a leaf spring 50, the opposite 35 end of which engages the V-shaped lug 44 in order to normally hold the angled member 38 in a position outwardly of the plate 13.

In operation, the device is attached to the 40 door 12 by means of the suction cup 18 or prong 23 and the forcing of the prongs 16 into the edge of the door. When in this position the arm 39 of the angled member 38 is positioned between the edge of the door and the door frame. The spring 27 is then wound by rotating the handle 37, the device being held against operation by the lug 44 engaging between the teeth of the gear 32. The lever 48 is then swung on its pivot so as to disengage the notch 45 in the arm 40 of the angled member 38 which permits said angled member to move slightly rearwardly until the arm 39 of the angled member 38 engages the edge of the door frame, which movement is not sufficient 45 to permit the disengagement of the lug 44 from the gear 32. The device then remains in this position while the door is closed, but upon opening the door the space between the same and the frame 10 is enlarged, 55 which permits the angled member 38 to be

moved outwardly with relation to the plate 13, due to the spring 35, until the lug 44 has disengaged the teeth of the gear 32, which will permit the gear 32 to rotate in order that the double action pawl may be 60 alternately turned which will cause the hammer to rapidly strike the bell 35 which will sound an alarm that may be readily heard. 70

When it is desired that the alarm not be sounded when the door is opened the lever 75 48 is moved so as to engage in the notch 45 which will hold the lug 44 of the angled member 38 in engagement between the teeth of the gear 32 while said lever 48 remains in such position so that the sounding of the 80 alarm will not be effected during the opening of the door.

Having thus described my invention, what I claim as new is:

1. A burglar alarm in combination with 85 a door and door frame, comprising a plate, means for attaching said plate to the door, spring operated means carried by said plate for sounding an alarm, a member slidably mounted upon said plate one end of which is 90 adapted to engage between the door and door frame, while the opposite end thereof engages said means for sounding said alarm to prevent operation thereof, spring means for moving said slidable member to disengage the 95 same from said alarm so that the same may be sounded when the space between the door and door frame is increased by the opening of the door, and means adapted to engage said slidable member for holding the same 100 against movement when desired.

2. A burglar alarm in combination with a door and door frame, comprising a plate, a pair of parallel spaced extensions formed on the opposite sides of the plate, a suction 105 cup having a reduced neck received between one pair of parallel spaced extensions arranged for frictionally engaging the side of the door, the opposite pair of parallel spaced extensions having the free ends thereof bent at right angles and extending between the door and door frame, prongs carried by the inner faces of said angularly bent portions for engaging into the door, a spring operated means for sounding an alarm carried by 110 said plate, an angular member slidably mounted on said plate with one arm thereof positioned between the parallel spaced extensions that are bent at right angles and between the door and door frame, means carried by said angular member for engaging the means for sounding an alarm in order to prevent the sounding of said alarm when the door is closed, and spring means for moving said angular member to disengage the means carried thereby from the means for sounding an alarm when the space between the door and door frame is increased 125 by the opening of the door.

3. A burglar alarm in combination with 130

a door and door frame, comprising a plate, a pair of parallel spaced extensions formed on the opposite ends of said plate, a rubber suction cup having a reduced neck 5 adapted to be received between a pair of parallel spaced extensions in order to hold said suction cup in position in frictional engagement with a door, a lever pivotally connected to one of the parallel spaced extensions supporting said rubber suction cup, a prong carried by said pivotally connected lever arranged to be forced into the door, the other of said pair of parallel spaced extensions having the free ends thereof bent 10 at right angles for extending between the door and door frame, means carried by the inner faces of said angularly bent portions for engaging the door, an angular member slidably mounted on said plate, one portion 15 of which is adapted to engage between the door and door frame and positioned between the right angularly bent portions, a spring operated means for sounding an alarm carried by said plate, and means carried by 20 said angular member for engaging said means for sounding an alarm when the door is in a closed position, and spring means for moving said angular member to disengage the means carried thereby from the means 25 for sounding an alarm when the space between the door and door frame is increased by the opening of the door.

4. A burglar alarm in combination with a door and door frame, comprising a plate, 30 means for attaching said plate to a door, a pair of parallel spaced extensions formed on said plate, said extensions having the free ends thereof bent at right angles and extending between the door and door frame, 35 an angled member having a slot in one arm thereof while the other arm is positioned between the bent portions of the parallel spaced extensions and between the door and door frame, a pin carried by said plate and 40 extending through said slot in said angular member, an upturned flange formed on the inner edge of one of the parallel spaced extensions for acting as a guide for the 45 slideable movement of the angled member on the plate, a spring operated means for sounding an alarm comprising a series of gears, a lug carried by said angled member for 50 engaging between the teeth of one of the gears of said means for sounding an alarm to prevent the sounding of the alarm 55 while the door is in a closed position, and a leaf spring secured to said plate and having the free end thereof engaging said lug for moving the same away from the gear when the space between the door and door frame is increased by the opening of the door.

5. A burglar alarm in combination with a door and door frame, comprising a plate, 60 means for attaching said plate to a door, a pair of parallel spaced extensions formed on said plate, said extensions having the free ends thereof bent at right angles and extending between the door and door frame, 65 an angled member having a slot in one arm thereof while the other arm is positioned between the bent portions of the parallel spaced extensions and between the door and door frame, a pin carried by said plate and 70 extending through said slot in said angular member, an upturned flange formed on the inner edge of one of the parallel spaced extensions for acting as a guide for the slideable movement of the angled member on the plate, a spring operated means for 75 sounding an alarm comprising a series of gears, a lug carried by said angled member for engaging between the teeth of one of the gears of said means for sounding an alarm to prevent the sounding of the alarm 80 while the door is in a closed position, a leaf spring secured to said plate and having the free end thereof engaging said lug for moving the same away from the gear when the space between the door and door frame is increased by the opening of the door, said angled member having a notch formed in 85 one edge thereof, and a lever pivotally connected to said plate and adapted to be swung into said notch in said angled member for preventing the disengagement of the lug carried by the angled member from the gear of the means for sounding an alarm 90 when said space is increased.

In testimony whereof, I have affixed my 100 signature.

CARL F. LOAR.
